TYPEWRITING MACHINE

William A. Dobson, Wethersfield, Conn., assignor
to Underwood Elliott Fisher Company, New
York, N. Y., a corporation of Delaware

Application April 2, 1941, Serial No. 386,510

10 Claims. (Cl. 197—63)

This invention relates to carriage-stop mechanisms for typewriting machines, and more particularly to margin-gaging mechanisms having provision for key setting of margin-defining stops selectively at substantially any letter-space increment of carriage travel.

The present invention is in the nature of an improvement over the key-settable margin-stop mechanism shown and described in my copending application Serial No. 376,045, filed January 27, 1941, now Patent No. 2,328,376, issued August 31, 1943. The carriage-stop mechanism therein described provides a series of letter-spaced, uniform stops settable individually by key operation of a stop setter, the stops being selectable by positioning the carriage. A single counterstop is provided with which any two set stops may cooperate to limit carriage travel in either direction to within a normal line length established by the particular stops selected. Any one stop being set may be adapted to define either the left-hand or right-hand margin of a typed line, provision being made to render the counterstop momentarily ineffective during setting of the stop, subsequent carriage movement in an appropriate direction being effective to release the counterstop at the proper side of the set stop. The carriage-stop mechanism also provides for margin release to permit typing beyond either margin defined by the set stops. Upon operation of the margin-release key, the normally effective counterstop is withdrawn out of the path of the set stops and so held by latching means releasable automatically when the carriage is returned to within the limits of the normal typing line.

The present invention is directed to provide an improved margin-release mechanism by which operation of the margin release is prevented unless the carriage is positioned at either margin, to thereby forestall unintentional margin release which would render the mechanism temporarily ineffective for margin-gaging purposes.

Another object of the invention is to provide a margin-gaging mechanism having a locking device associated with the normally effective counterstop adapted to be retracted to effect margin release, the locking device being normally effective to obstruct full retraction of the counterstop and being rendered ineffective when the latter is engaged by either of the margin-defining stops.

A further object is to provide a key-settable margin-gaging mechanism having a device for adapting any selected stop to function selectively either as a right- or left-hand margin stop, by appropriate carriage movement after stop setting, the device being also adapted to lock the retractable counterstop in its normal projected position unless rendered ineffective by cooperation of the margin-gaging stops therewith.

Other objects and advantages will hereinafter appear.

In the drawings:

Figure 1 is a transverse sectional view taken on a fore-and-aft plane of a typewriter embodying the margin-gaging mechanism of the invention,

Figure 2 is a fragmentary front elevational view of the margin-gaging mechanism in its normal condition for gaging the line ends of a typing line,

Figure 3 is a transverse section through the mechanism, taken on a line 3—3 of Figure 2,

Figure 4 is an elevational view similar to Figure 2 but showing the mechanism operated for margin release preparatory to typing beyond the normal line ends,

Figure 5 is a view similar to Figure 2 but showing the condition of the mechanism upon an attempted operation of margin release with the carriage in an arbitrary position intermediate the normal line ends defined by the set stops,

Figure 6 shows the mechanism conditioned for margin release in that the carriage is at line-start position as gaged by the left-hand margin stop,

Figure 7 is a view similar to Figure 6 but showing the mechanism conditioned for margin release with the carriage at the typing-line-end position as gaged by the right-hand stop, and

Figures 8 and 9 are views illustrating successive intermediate stages in the operation of the mechanism to institute margin release from the Figure 7 condition.

The general operation of the typewriting machine, insofar as it pertains to the use and advantages of the present invention, will be described in reference to Figure 1. A carriage 10 supports a platen 11 and is mounted by trackways 12 for line typing and return travel on a main frame 13 of the machine. A spring drum 14 actuates the carriage in line-typing direction under control of a letter-feed escapement mechanism 15 which includes an escapement wheel 16 geared to a rack 17 on the carriage by a pinion 18. The typing instrumentalities may be of any known kind, including type bars 20 that are actuatable to strike against the platen 11 by type keys, not shown. The escapement mechanism is operated to letter feed the carriage at each imprint of a type by engagement of the type bars 20 with a universal bar 21, in the usual manner. In consequence of each type-key operation, the carriage is advanced step by step in letter-space intervals to type the characters along a typing line, upon completion of which, the carriage is manually returned to line-start position.

The normal line ends of carriage travel are defined by the cooperation of certain set stops on the carriage with a counterstop on the main frame. The stop organization includes a rack

bar 22 on the carriage supporting a series of stops 23 arranged at letter-spaced intervals. Each stop is settable selectively from an ineffective position to an operative position at which the stop may engage the counterstop. A detent spring 24 held on the rack bar 22 coacts with each of the stops 23 to yieldably hold same at the selected position, each stop having a series of detent notches cooperative with the detent spring.

The stops 23, as shown, have three detent notches so that each stop may be set to a second operative position in which it may function as a tabulator stop, and the stops each have an offset tab for cooperation with a second counterstop not shown. The stop organization may thus function in a carriage stop mechanism adapted both for margin gaging and tabulating, in accordance with the disclosure of my copending application Serial No. 372,622, filed December 31, 1940, now Patent No. 2,328,375, issued August 31, 1943. Insofar as the present invention is concerned, however, a clear understanding of its operation will be had in considering only the mechanism for margin gaging, including the features of right- and left-hand stop selection and margin release. It will be understood, however, that the invention is adaptable as well to mechanisms intended for both margin gaging and tabulating.

The stop-setting mechanism is operable by a key to selectively set any of the stops 23 positioned opposite a stop setter 25 by appropriately locating the carriage 10 at the desired letter space in its range of travel. The stop setter 25 is positioned laterally of the main frame 13 at a prescribed point in fixed relation to the printing point of the typewriter. The type guide at the printing point may serve as an indicator of the stop setting point to assist the typist in locating the carriage at the desired letter spaces at which the margins are to be set. The stop setter 25 is mounted for vertical reciprocation on a bracket plate 26 which may form part of the main frame of the machine, and has its lower end flexibly connected to an arm 27 held on a shaft 28 which has a second arm 29 secured thereto. A stop setting key 30 is carried on a lever 31 fulcrumed at 32 on the main frame and connected by a link 33 to said arm 29. The key 30 is so mounted on the lever as to be selectively operable to make effective either of two limiting means which determine whether a stop 23 will be set half way for tabulating or full way for margin gaging. When the key 30 is operated to the position shown in phantom in Figure 1, the stop setter is moved through a stroke sufficient to set the stop to its effective position for margin gaging. The stop setter 25 and its operating train to the key 30 are restored to inactive position by a spring 34. A key-operable stop restorer, not shown, may be provided to restore the set stops to ineffective position on the rack 22 when a new stop selection is desired.

The mentioned counterstop cooperable with the set stops to arrest carriage travel at prescribed margins, is indicated at 35, see Figures 2 and 3. For purposes hereinafter manifest, the counterstop 35 is mounted for vertical reciprocation so as to be retractable from its normal position in the path of the set stops to a position out of the stop path and is mounted also for swinging movement in the direction of carriage travel. The lower end of the counterstop provides a slotted portion 37 which rides on a stud 38 secured to the bracket plate 26. A yoke plate

39, also secured to said bracket plate, straddles the counterstop 35 and associated elements, and carries a right-hand stop lug 40 and a left-hand stop lug 41 which limit the swinging movement of the counterstop. A spring 42 anchored on plate 39 yieldably holds the counterstop in its normal raised position and, being active on an offset arm 43 of the counterstop, holds the latter normally in a rightward position against the lug 40. In its normal position, the counterstop has its stop-engaging portion just to the right of the point at which the stops are set, see Figure 2.

The counterstop 35 is swingable to either of two positions, defined by the lugs 40 and 41, see Figures 6 and 7, in order that the counterstop may arrest a set stop 23, whether serving for right- or left-hand margin gaging, at the same position, which position corresponds with that at which the stops are set by the stop setter 25. It may be here noted in reference to Figure 6, that in arresting the carriage at line-start position, the left-hand stop drops back a fractional letter space after engaging the counterstop. This drop-back, in varying extents, is usual in margin-gaging mechanisms, being necessary to allow the letter-feed escapement to again assume control of the carriage after the latter has been actuated in a return run. The position at which the left-hand stop comes to rest, as shown in Figure 6, corresponds, however, with that at which the stops are set. As shown in Figure 7, the right-hand stop is also arrested at said position upon banking against the counterstop, the stop lug 41 being arranged to so arrest the said carriage stop.

While the lateral displacement of the counterstop 35, as described, is primarily intended to afford corresponding arrest positions for both the right- and left-hand stops, the leftward swinging of the counterstop, incident to gaging the line end or right-hand margin, may also be employed to actuate a line-lock device to render the typing instrumentalities inoperative. For this purpose, a lever 36, see Figure 1, has an end thereof disposed for engagement by the counterstop 35. A block 47 carried on said lever is adapted to obstruct operation of the letter-feed escapement mechanism 15 when the counterstop is swung to the Figure 7 position. In blocking the escapement, the universal bar 21 is rendered inoperative and the type bars 20 are thus stopped before striking the platen. When the counterstop assumes its normal rightward position, a spring, not shown, restores the lever 36 to normal position at which the block 47 is clear of the escapement mechanism.

Any one of the stops 23 of the series set for margin gaging may be adapted to function either as a left-hand stop to determine the line-start position, or as a right-hand stop to determine the line-end position of the carriage. The adaptation of a set stop for either function is accomplished, following the setting of the stop, by moving the carriage in an appropriate direction. For this purpose, a buttress 44 is pivotally mounted on the counterstop 35 and is arranged to overlap the stop-engaging portion thereof, extending to the left beyond said portion so as to project into the station at which the stops are set. The top edge of the buttress is arcuate on a radius from its pivotal center so as to clear the stop rack 22 in all angular positions of the buttress. The buttress 44 is yieldably held in normal position by a spring 45 interposed between a lower arm of the buttress and the counterstop. Spring 45

urges the buttress to rotate counterclockwise, as viewed in Figure 2, to its normal position defined by a lug 46 of the buttress engaged with an inner edge of the counterstop.

It will be apparent that when setting the stops 23 for margin gaging, none of said stops are engaged with the counterstop and the latter is, therefore, in its normal upright position, Figure 2, held by spring 42 against the stop lug 49. As one of the stops 23 is set by the actuation of the stop-setter 25, the lower end of the stop engages the buttress 44 and presses the counterstop downward to a position out of the path of the set carriage stops, against the tension of spring 42 which still urges the counterstop upward. If the set stop is intended for right-hand margin gaging, the carriage is then moved to the right, during which the stop, moving with the carriage and riding along the top edge of the buttress or swinging the buttress with it, travels to the right side of the counterstop and thence off the buttress so that the counterstop is released and assumes an effective position at the left side of the set stop. When it is intended that the set stop function to gage the left margin, the carriage is moved leftward after setting the stop, and the set stop riding along and off the buttress allows the counterstop to be released at the right side of the set stop. Thereafter, this set stop will cooperate with the counterstop to gage the line-start position of the carriage. The stops 23 set for right- and left-hand margin gaging are indicated at 23^r and 23^l, respectively. It may be here noted that the buttress 44, in regard to its stop-adapting function just described, is pivotally mounted in order that same may swing out of the way when the carriage is banked at line-start position, see Figure 6, that is, in order that the left-hand stop 23^l may directly engage the counterstop. By following the procedure described, a stop 23 is set for margin gaging adjacent each end of the carriage, the two stops 23^r and 23^l defining a line-typing zone, into which zone the counterstop 35 projects for interception of the margin-gaging stops moving with the carriage in either direction. This feature of the mechanism by which a set stop may be adapted for either right or left margin gaging selectively, forms the subject matter of my copending application Serial No. 376,045, now Patent No. 2,328,376.

The mechanism is adapted for margin release, being operable to retract the counterstop out of the carriage stop path, to allow the carriage to be moved outside the normal line-typing zone for typing beyond either prescribed margin. It will be observed that when margin release is desired, the carriage usually has been banked at one of the margins and, therefore, the carriage stop defining that margin is engaged with the counterstop. The mechanism is thus conditioned as shown in either Figures 6 or 7, depending on which margin has been reached. It will also be observed that when the carriage is banked at line-end position, Figure 7, the carriage stop 23^r has swung the counterstop over against the lug 41. From either the Figure 6 or Figure 7 position, the counterstop 35 is retracted to institute margin release, by pressing a margin-release key 48, Figure 1. This key is connected by a push rod 49 to an arm 50 of a rockable member 51 which has a second arm 52 flexibly connected to the lower end of counterstop 35, being engaged in a slotted portion 53 thereof.

A latching device is provided, as shown best in

Figures 2, 3, and 4, to hold the counterstop retracted during the typing beyond either margin, said latching device being released by return of the carriage to its normal line-typing zone, thereby automatically restoring the mechanism for its normal margin-gaging function. A resilient latch member 54 is mounted for pivotal and endwise movement by a stud 55 on the latch member, engaged in a vertically elongate slot 56 in the yoke plate 39. A tension spring 57 yieldably holds the latch member down with the stud 55 bottoming in the slot. The spring 57 is arranged to exert its force on the latch member 54 in a substantially perpendicular line from the center of stud 55 so as to yieldably hold the latch member in a normally upright position. The lower end of the latch member is inclined toward the counterstop to provide a bevel 58, see Figure 3. As the counterstop is retracted, a catch 60 thereon cooperating with the bevel 58, flexes the latch 54 outwardly until the catch 60 is engaged under the lower end of the latch. When the counterstop is retracted from the Figure 6 position upon operation of the margin-release key 48, the counterstop moves downwardly until its catch 60 is engaged under the latch, after which the release key 48 is released. The counterstop, under influence of its spring 42, then starts back toward its normal projected position, carrying with it

the latch member 54 against the tension of its spring 57, until stud 55 engages the upper end of slot 56. Under this condition, the counterstop is still held retracted but a finger 61 of the latch member 54 is projected into the carriage-stop path. This same action takes place when the counterstop is retracted from the Figure 7 position, except that in this instance the counterstop assumes the upright position only after riding off the carriage stop, and thereafter continues downwardly until the latching takes place. In either instance, after the release key 48 has been depressed and then released, the counterstop and latch assume the condition shown in Figure 4, and the carriage stop is beyond the counterstop, allowing carriage travel beyond the margin. To complete margin release from the Figure 6 position, the carriage is moved rightward before the release key is freed. In this way, the carriage stop 23^l is brought to the right of the counterstop before the latch finger 61 is advanced to effective position. However, when margin release from the Figure 7 position is instituted, the resultant rightward swinging of the counterstop automatically positions the carriage stop 23^r to the right thereof in readiness for typing beyond the right-hand margin or line end.

When the carriage is restored to its normal line-typing zone from beyond either margin, the carriage stop 23 traveling with the carriage, engages the latch finger 61 and trips the latch 54 thereby automatically restoring the counterstop to its normal effective position in the path of and between the set carriage stops 23^r, 23^l. The margin-release mechanism, including the features of automatic restoration, as just described, forms the subject matter of my copending application Serial No. 376,046, filed January 27, 1941, now Patent No. 2,328,377, issued August 31, 1943.

As aforeindicated, the present invention is directed to provide certain improvements in the margin-release mechanism of my copending application Serial No. 376,046, Patent No. 2,328,377 by which operation of said mechanism is prevented unless the carriage is banked at either margin; that is, unless either of the stops 23^r or 23^l is

engaged with the counterstop; thereby to fore-stall unintentional margin release which would render the margin-gaging mechanism temporarily ineffective. The improvements herein also relate to my copending application Serial No. 376,045, now Patent No. 2,328,376, in that the member or buttress 44 by which right- and left-hand stop selection is afforded, also constitutes part of the means by which the unintentional margin-release operation is forestalled.

In view of its further purpose in the present invention, the buttress 44 may be regarded as a locking member in that it serves to lock the counterstop projected when the latter is free of the carriage stops. Accordingly, member 44 carries an abutment or barrier 62 which, in the normal position of member 44, is adapted to engage the stop 40 when an attempt is made to operate the margin release with the carriage positioned intermediate the margins. Under such conditions, when the release key 48 is pressed, see Figure 5, the abutment moves bodily with the counterstop as the latter is initially retracted, and engages lug 40. Upon release of key 48, spring 42 merely returns the counterstop to its normal position, see Figure 2.

The locking member 44, however, is swung to unlocked position when either of the carriage stops 23^r and 23^l is engaged with the counterstop; that is, when the carriage is arrested at either margin. Carriage arrest at the left-hand margin produces the condition shown in Figure 6 in which stop 23^l, engaging the wing of locking member 44, has rotated same against the tension of its spring 45 to a position in which the abutment 62 is clear of lug 40. Thus, the counterstop 35 is unlocked and may be fully retracted to the margin-release position shown in Figure 4, upon operation of the margin-release key 48. It will, of course, be noted that as soon as the counterstop 35 is fully retracted, the locking member 44, riding off the carriage stop 23^l, snaps back to its normal position under influence of spring 45, so that when the counterstop is again released, the locking member 44 is in position to again prevent margin release except under the conditions stated.

It may be here noted that, with the mechanism in normal condition, Figure 2, the abutment 62 of member 44 is spaced from the lug 40 a distance ample to allow the counterstop 35 to be retracted out of the path of stops 23, but not sufficient to let the counterstop be latched in retracted position by the latch 54. This initial retraction of the counterstop, as gaged by the spacing of abutment 62 from lug 40, is necessary in stop setting, to allow the counterstop to be retracted out of the stop path, so that when the carriage is subsequently moved the set stop may pass over the counterstop to a position to the right thereof, according to the function of member 44 as previously described.

The operation of the mechanism for unlocking the counterstop from the condition assumed in gaging the right-hand margin or line-end position of the carriage, is shown best in Figures 7, 8 and 9. The locking member 44 has an inclined arm 64 which, in the leftwardly displaced position of the counterstop, engages with a prong 65 on the yoke plate 39. Said arm is offset forwardly from the plane of member 44 so as to maintain contact with the prong. The prong 65 terminates just in front of the body portion of member 44 to allow the latter to assume the Figure 7 position. As the margin-release key 48

is pressed, counterstop 35 is initially retracted to the position shown in Figure 8 at which the counterstop is about to ride off carriage stop 23^r. While the counterstop moves to this position, the engagement of arm 64 with prong 65 is maintained, the displacement of the locking member pivot causing member 44 to rotate to such position that the abutment 62 is below the stop 40. Thus, as the counterstop leaves the carriage stop, with the result that the counterstop is allowed to swing rightward as shown in Figure 9, the abutment 62 is well below lug 40 so that its locking engagement therewith is prevented, even though spring 45 urges member 44 to its normal locking position. Thereafter, the counterstop is fully retracted and is so latched, thereby assuming the position shown in Figure 4 with member 44 restored in readiness for its locking function when the counterstop is again released.

What is claimed is:

1. In a typewriter having a frame and a carriage movable in opposite directions on the frame; a stop and a counterstop mounted one on the frame and the other on the carriage, the counterstop being engageable with the stop to halt carriage movement in one direction; means to move the counterstop to a holding position clear of the stop, to release the carriage for additional movement; means to releasably hold the counterstop so moved; means including a barrier to prevent movement of the counterstop to said holding position; and means, rendered effective upon stop and counterstop engagement to disable said preventing means.

2. In a typewriter having a frame and a trav- 35 elable carriage, in combination, a stop and a counterstop mounted one on the frame and the other on the carriage, said counterstop being movable between a position engageable with said stop and a retracted, latching position clear of said stop, means for moving the counterstop to said retracted, latching position, latching means to releasably hold the counterstop retracted when moved to the latching position, means to ob- 40 struct counterstop retraction to latching position, and means, operable by said stop, to render the last-said means ineffective.

3. In a typewriter having a frame and a trav- 50 elable carriage, in combination, a stop and a counterstop mounted one on the frame and the other on the carriage, said counterstop being movable between a position engageable with said stop and a retracted, latching position clear of said stop, means for moving the counterstop to said retracted, latching position, latching means to releasably hold the counterstop retracted when moved to the latching position, and a movable locking member normally obstructing counter- 55 stop retraction to latching position but engageable and movable by said stop to allow counterstop retraction.

4. In a typewriter having a frame and a trav- 65 elable carriage, in combination, a stop and a counterstop mounted one on the frame and the other on the carriage, said counterstop being movable between a position engageable with said stop and a retracted, latching position clear of said stop, means for moving the counterstop to said retracted, latching position, latching means to releasably hold the counterstop retracted when moved to the latching position, and a member 70 movably carried on said counterstop and ob- structing counterstop retraction to latching position, said member being movable by said stop,

when approaching the counterstop, to a position allowing counterstop retraction.

5. In a typewriter having a frame and a trav-
elable carriage, in combination, a stop and a counterstop mounted one on the frame and the other on the carriage, said counterstop being movable between a position engageable with said stop and a retracted, latching position clear of said stop, means for moving the counterstop to said retracted, latching position, latching means to releasably hold the counterstop retracted when moved to the latching position, a member mounted on said counterstop for movement between a position obstructing counterstop retraction to latching position and a second position allowing said retraction, and means urging said member to obstructing position, said member being engageable and movable by said stop to said second position.

6. In a typewriter having a frame and a trav-
elable carriage, in combination; a series of stops arranged at letter-space intervals on the carriage for setting to effective position; key-operable means for setting any one of said stops, positioned by carriage movement, at a stop-set-
ting station; a counterstop on the frame adjacent said station, mounted for movement between an effective position engageable with the set stop and a retracted, latching position clear of the set stop; means urging the counterstop to the effective position; means for retracting the counterstop to the latching position; latching means to releasably hold the counterstop retracted when moved to latching position; and a member pivoted on said counterstop and yieldably held in a position in which a part of said member is disposed in said stop-setting station, said member having an abutment obstructing counterstop retraction to latching position and being adapted to be engaged and moved pivotally by a set stop during carriage travel, to withdraw the abutment and thus permit said counterstop retraction.

7. In a typewriter having a frame and a trav-
elable carriage, in combination; a series of stops arranged at letter-space intervals on the carriage for setting to effective position; key-operable means for setting any one of said stops, positioned by carriage movement, at a stop-set-
ting station; a counterstop on the frame adjacent said station, normally urged to effective position in the path of the set stop; a member pivoted on said counterstop and yieldably held in a normal position in which a part of said member is disposed in said stop-setting station for engagement by a stop being set, to thereby initially retract and so hold the counterstop in setting the stop, until a subsequent carriage movement moves the set stop out of said station, thereby releasing the counterstop at one side of the set stop; margin-
release mechanism including means for retracting the counterstop beyond initially retracted position and clear of the stop and means to releasably hold the counterstop so retracted; said member having an abutment normally obstructing counterstop retraction beyond initially retracted position, said member being adapted to be engaged and moved pivotally by the set stop during carriage travel to withdraw the abutment and thus permit counterstop retraction and latching for margin release.

8. In a typewriter having a frame and a re-
ciprocating carriage, in combination; a series of selectively key-settable stops on the carriage, any two of said stops that are set being adapted to

define the normal line ends of carriage travel; a counterstop mounted on the frame for shifting in the direction of carriage travel between two positions, said counterstop being also movable between an effective position engageable with the set stops and a retracted, latching position clear of said stops; means for retracting the counterstop to said latching position; latching means to releasably hold the counterstop retracted when moved to the latching position; a locking member movably mounted on the counterstop for movement bodily therewith and obstructing counterstop retraction to latching position; and means, operative upon counterstop engagement by one or the other of the set stops, depending on the direction of carriage travel, to render said locking member ineffective in the corresponding, shifted position of the counterstop.

9. In a typewriter having a frame and a recip-
rocating carriage, in combination; a series of se-
lectively key-settable stops on the carriage, any
20 two of said stops that are set being adapted to
define the normal line ends of carriage travel;
a counterstop mounted on the frame for shifting
in the direction of carriage travel from a normal
25 position to a displaced position; said counterstop
being also movable between an effective position
engageable with the set stops and a retracted,
latching position clear of said stops; means yield-
30 ably holding the counterstop in said effective po-
sition; means for moving the counterstop to said
retracted, latching position; latching means to
releasably hold the counterstop retracted when
35 moved to the latching position; and a member
pivoted on said counterstop and having an abut-
ment which, in the normal position of the coun-
terstop, obstructs counterstop retraction to the
latching position; said member being adapted, in
40 the normal position of the counterstop, for en-
gagement by a set stop to withdraw the abut-
ment; and said member having means which, in
the displaced position of the counterstop, coacts
with the frame to swing said member during sub-
45 sequent counterstop retraction and thereby ren-
der said abutment ineffective.

10. In a typewriter having a frame and a re-
ciprocating carriage, in combination, a series of
50 stops arranged at letter-space intervals on the carriage for setting to effective position, key-op-
erable means for setting any one of said stops, positioned by carriage movement, at a stop-set-
ting station, a counterstop mounted on the frame for retraction out of the stop path and for shift-
ing in the direction of carriage travel from a nor-
55 mal position just to the right of said station to a displaced position just to the left of said station, means yieldably holding the counterstop in said normal position and in the stop path, margin-
release mechanism including means for retract-
ing the counterstop to a holding position out of
60 said path and means to releasably hold the coun-
terstop so retracted, and a member pivoted on
said counterstop and yieldably held in a normal
position in which said member is disposed in said
65 station, said member having an abutment nor-
mally obstructing counterstop retraction to said holding position, said member being adapted, in
the normal counterstop position, for engagement
by a set stop to withdraw the abutment, said
70 member having a portion which, in the displaced
counterstop position, coacts with the frame to
swing said member and thus render the abut-
ment ineffective during subsequent counterstop
retraction.
